COMBINATION FINE TUNING AND SLEWING DEVICE

Samuel L. Broadhead, Jr., Cedar Rapids, and Harry W. Lehman, Marion, Iowa, assignors to Collins Radio Company, Cedar Rapids, Iowa, a corporation of Iowa

Application November 24, 1958, Serial No. 775,755

2 Claims. (Cl. 74—10.8)

This invention relates generally to improvements in tuners for electronic equipment, and more particularly to a simple and effective combined coarse and fine tuning mechanism.

The primary object of this invention is to provide an improved tuning mechanism including gearing active over a portion of its operation to effect fine tuning and active over other portions of its operation to effect coarse tuning.

A more specific object of this invention is to provide an improved tuning mechanism including a fine tuning drive operative between two spaced, coarse drives with the drives being consecutively operable in either direction.

Another object of this invention is to provide an improved tuning mechanism including plural power paths between an input drive shaft and an output shaft, one of the paths effecting coarse tuning and the other path being effective only during a portion of a power input cycle to effect fine tuning between stages of coarse tuning.

With the foregoing and other objects in view, the invention resides in the following specification and appended claims, certain embodiments and details of construction of which are illustrated in the accompanying drawing wherein the tuning mechanism comprising the invention is illustrated in a partially sectioned plan view.

Referring more particularly to the drawing, the tuning mechanism includes a housing 1 to which is secured by any suitable means (not shown) a reversible driving motor 2. The motor 2 directly drives the input shaft 3 of the tuning mechanism. The shaft 3 carries a drive gear 4 which is of substantial length within the confines of housing 1.

Rotatably supported on housing 1 by suitable journals 5 and 6 is an output or driven shaft 7 which actuates condensers or inductors, not shown. Within the housing the shaft 7 fixedly carries a driven gear 8 which includes an integral hub 9. As illustrated, the hub 9 of gear 8 is positioned adjacent the inner wall of housing 1. Adjacent the journal 6 the shaft 7 is provided with an integrally mounted abutment 10. Intermediate the face of gear 8 and the abutment 10 the shaft 7 is threaded at 11 to receive in threaded relationship thereon a traverse gear 12. The teeth 13 of gear 12 continuously mesh with the teeth of drive gear 4 over the full range of travel of the traverse gear between gear 8 and abutment 10.

Spaced from the output shaft 7 and carried by journals 14 and 15 within housing 1 is an idler shaft 16. As illustrated, the shafts 3, 7, and 16 are mounted in spaced parallel relationship with the shaft 7 constituting in effect an intermediate shaft. The shaft 16 fixedly carries a gear 17 of substantial length. The teeth of gear 17 mesh with the teeth 13 of traverse gear 12 over a portion of its travel between gear 8 and abutment 10. The period of engagement is controlled by the length of gear 17. In the preferred design gear 17 is positioned directly opposite gear 4 and is somewhat shorter in the axial dimension than gear 4 so that traverse gear 12 will dis-

2

engage gear 17 as it approaches the completion of its travel along thread 11 of shaft 7 in either direction. Shaft 16 also carries a pinion 18 which continuously meshes with gear 8.

5 A power supply, not shown, is connected to suitable terminals 23 and 24. A switch box 19 is connected to terminals 23 and 24 and has a knob 20 movable from "S" or "stop" position to "F" or "forward" position or to "R" or "reverse." Leads 22 connect the switch box 19 to the motor 22.

10 The motor 2 may be controlled by knob 20 so that it runs forward, reverse, or is stopped.

When the gear 12 engages gear 17 the shaft 7 will be driven slower than when gear 12 is out of engagement with gear 17. Thus, by controlling the direction of rotation of the motor 2, the relationship between shafts 3 and 7 may be varied.

15 The operation of the tuning mechanism should be obvious to one skilled in the art. With the traverse gear 12 in the position shown in unbroken lines, assume that a signal is sent to motor 2 to adjust the tuning by moving shaft 7 over a considerable frequency range. Depending on the direction of rotation of gear 4, the gear 12 will be rotated and hence moved axially of the shaft 7 along thread 11 in one direction or the other and eventually will reach either of the two broken line positions indicated for gear 12. While gear 12 remains in mesh with gear 17, a drive path is maintained from gear 4, through gears 12, 17 and 18 to output or driven gear 8. This drive path constitutes a fine tuning path for the output shaft 7 and assist in reaching a precise frequency level. If the signal received by motor 2 is sufficient to drive the tuner to a widely spaced position from its previous setting, then a rapid movement of shaft 7 is de-

20 sired to reach the new position as quickly as possible. Rapid traverse is obtained in this tuning mechanism as soon as the traverse gear engages either the face of gear 8 or the abutment 10, for at this position the teeth 13 of gear 12 are out of mesh with gear 17 and the drive path 25 is directly from gear 4 to the gear 12, now locked against gear 8. This drive path constitutes a fine tuning path for the output shaft 7 and assist in reaching a precise frequency level. If the signal received by motor 2 is sufficient to drive the tuner to a widely spaced position from its previous setting, then a rapid movement of shaft 7 is de-

30 sired to reach the new position as quickly as possible. Rapid traverse is obtained in this tuning mechanism as soon as the traverse gear engages either the face of gear 8 or the abutment 10, for at this position the teeth 13 of gear 12 are out of mesh with gear 17 and the drive path 35 is directly from gear 4 to the gear 12, now locked against axial movement, and to the shaft 7. The shaft 7 may overshoot the newly signalled tuning position. If this occurs, the knob 20 may be moved to change the direction of rotation of motor 2. The traverse gear 12 will 40 move away from its locked position against the gear 8 or abutment 10 and the teeth 13 will reengage gear 17 to effect a fine tuning drive so that a true or precise null may be reached at the new frequency level.

45 Thus it should be apparent to one skilled in the art that the tuning mechanism provides a simple and effective pair of drive paths co-acting with one another so that a fine tuning movement of an output shaft is effective, in either direction of rotation of an input shaft, between two effective coarse tuning motions, to enable the mechanism to rapidly seek an approximate new frequency level and then seek out an exact or null position.

50 It is realized that the details of the invention may be subject to various structural modifications well within the knowledge of these inventors, who intend only to be limited to a liberal interpretation of the appended claims.

We claim:

55 1. A tuning control mechanism for radio equipment comprising an input shaft, a drive gear of substantial length mounted on said input shaft, an output shaft, said output shaft including a pair of spaced stop means and a threaded periphery between the stop means, a traverse gear mounted in threaded engagement with the output shaft between the stop means and being in continuous engagement with the drive gear, an idler shaft, a gear mounted on the idler shaft for limited engagement with the traverse gear, a pinion gear mounted on the idler shaft, and an output driving gear mounted on the output

shaft and engaging the pinion gear, said output gear functioning as one of the stop means, said drive gear acting in either direction of rotation to move the traverse gear lengthwise of the output shaft, said traverse gear when driven against either stop means creating a coarse movement gear path for the output shaft and said traverse gear in its limited engagement with idler shaft gear during movement along the output shaft between the stop means creating a fine movement gear path for the output shaft.

2. A tuning control mechanism for radio equipment comprising a drive shaft, first gear means carried by said drive shaft, an intermediate shaft constituting an output shaft mounted in said mechanism in spaced relationship to said first gear means, said intermediate shaft being helically threaded over its length, a second gear means mounted on said intermediate shaft and having internal threads mating with the threads of said shaft, said second gear means being in continuous engagement with said first gear, an idler shaft carried by said mechanism, a third gear carried by said idler shaft, said third

5 gear being of a lesser width than the lengthwise dimension of the intermediate shaft, a pinion gear carried by said idler shaft, and a driven gear carried by said intermediate shaft, said driven gear and said pinion gear being in continuous engagement, said first gear means acting through said second and third gears and the pinion and driven gears to rotate the intermediate shaft to obtain a fine tuning output, said first gear acting through said second gear to directly drive the intermediate shaft for coarse tuning when said second gear is moved from engagement with the third gear means in either direction of travel by the threaded intermediate shaft.
